TRAFFIC CONTROL SIGNAL

Percy Bailey Renshaw, Liverpool, England, assignor, by mesne assignments, to Automatic Telephone & Electric Company Limited, London, England

Application June 22, 1933, Serial No. 677,029
In Great Britain June 30, 1932

10 Claims. (Cl. 177—337)

The present invention relates to traffic control signals for use at road crossings or the like and is more particularly concerned with a progressive type traffic control system by means of which a number of controllers located at successive crossings on a main road may be regulated from a master timer in a certain phase relationship to each other, so that if the average speed of the traffic is known it is possible to time the control signals so as to ensure a substantially continuous flow of traffic along the main road. Systems of this type have been found to give good results in use but their operation is not particularly flexible in that they require the controllers to be individually set as regards their time periods in the cycle, and a further disadvantage is the danger that all controllers will cease to function in the event of a breakdown at the master timer.

From the point of view of the traffic engineer in charge of the system, individual setting of the controller is undesirable and definitely precludes quick adjustment of the time cycle since each controller requires a personal visit. By far the more satisfactory arrangement is for complete control to be exercised from some master point where the necessary traffic data and timing charts for the whole system are readily available. It is also desirable that service shall be maintained even if the master timer fails and although this latter event is extremely improbable, the possibility of a complete stoppage of all controllers along an important route should preferably be eliminated. Accordingly the object of the present invention is to provide an improved system of the type described which obviates the shortcomings mentioned and provides in a particularly reliable manner the improvements mentioned.

According to one feature of the invention in a progressive system of traffic control the individual controllers are operated by impulses transmitted thereto at different times from a master timer so that their phase relationship may be altered at the master timer.

According to another feature of the invention in a progressive system of traffic control in the event of a complete failure of the master timer the individual controllers which are normally regulated thereby continue to function owing to the provision of independent timing apparatus.

The invention will be better understood from the following description of one method of car-

rying it into effect, reference being had to the accompanying drawings, in which Figs. 1 and 2 show by way of example a master timer arranged to regulate three controllers of which the circuit connections for one are shown in detail, Fig. 3 shows one form of individual traffic actuated controller and system which may be controlled by the master controller, and illustrates in more detail the embodiment shown in brief in the rectangle of heavy dash lines in Figure 2; Fig. 4 illustrates another form of individual traffic actuated controller, in which traffic actuating devices may be employed in each road, and illustrates an arrangement whereby certain maximum periods of right of way may be controlled by the master timer.

It should be explained generally that the system comprises a master timer from which separate pairs of conductors radiate to each controller for the purpose of regulating their time periods in relation to each other. The controllers may be conveniently of the general type disclosed in British specification No. 355,741 but for the purpose of the illustration in Figure 1 and Figure 2 may be arranged to operate at fixed time periods independent of the traffic flow, that is to say, there is no question of extending their normal period as a result of a continuous flow of traffic passing over a road contact or the like. These controllers will be set to operate at rather long periods, considerably in excess of that required in the progressive system, but the periods will be curtailed by the right amount upon the reception of so-called "light" and "heavy" pulses over the control leads from the master timer.

Referring now to the circuit shown, the system is arranged for operation from A. C. mains and suitable rectifying arrangements are provided for obtaining direct current to operate the relays and neon lamps. In the drawing the alternating current mains designated 10 and 11 are shown incoming from the left hand side of Fig. 1 and for the operation of the master timer a tapping is made from these leads by way of the fuses FUS and main switches MNS to the primary winding of the transformer XFR. This transformer is provided with three secondary windings, two of which connect with the thermionic valve amplifier VLV which supplies direct current of the order of 400 volts to the terminals designated + and — in a circle, for the purpose of flashing the neon lamp N. The third winding on the secondary side of the transformer XFR connects with the full wave metal rect-

ifier bridge MRA which supplies direct current of the order of 50 volts to the terminal points marked + and - in a square, for the purpose of operating the relay F and the driving magnet DSM. Essentially the master timer comprises a rotary step-by-step switch DST of the type used in automatic telephone systems which may be completely immersed in oil and arranged to be operated step by step from a neon lamp im-
10 pulser, the speed of which may be altered by varying the setting of the resistance switch 12 connected in series with the condenser QB.

As regards the automatic stepping circuit it should be explained that when the neon lamp N flashes as the result of the charging of the condenser QB to the required voltage, relay E is operated in series therewith, thereby at armature e1 operating relay F, and at armature e2 connecting negative potential to the wipers of the switch DST. Relay F on operating, at armature f2 completes the circuit for the driving magnet DSM, at armature f1 supplements the connection to the wipers of the switch DST, at armature f3 shunts the neon lamp N and relay E by way of resistance YB, and at armature f4 flashes the master fail alarm lamp MFA. Relay E thereupon releases and upon the release of relay F after its slow period due to the copper slug on its core, the driving magnet is de-energized to advance 20 the wipers on to the next set of bank contacts. This action continues automatically so long as the system is in service. One bank and wiper of the switch DST is allotted to each controller to be regulated and the control leads extend from the appropriate contacts in the associated bank. Bank 1a connects with controller No. 1 of which only the regulating relays have been shown in the dotted rectangle; this controller may be located adjacent to the master timer. Bank 2a connects with controller No. 2 shown in Fig. 2, and bank 3a connects with controller No. 3, which is not shown as it is assumed to be identical with controller No. 2.

In the drawings each control lead is shown as making two connections with its associated bank, one of which is direct and the other extends by way of a resistance. Consequently as the switch rotates so-called light and heavy pulses are delivered over the control leads to the respective controllers in turn.

50 The control leads may comprise light gauge wires, for example, telephone lines, and terminate in the controllers on a pair of relays B and C shown in Fig. 2 connected in series one of which is marginal. As a result of the operation of one or both of these relays from the light and heavy pulses the signal lights of the controller are regulated accordingly.

In this particular example the complete cycle 60 time of the system is represented by 25 steps of the rotary switch DST in the master timer. Each step of the switch therefore represents 4% of the total cycle time so that by varying the connection of the control leads to the banks the phase relationship between the different sets of control signals may be adjusted to a very fine degree.

Each of the controllers, which are all identical, comprises essentially a battery of cams mounted on a common shaft and arranged to close contact springs in a particular order. As regards the No. 70 2 controller shown in Fig. 2 it should be explained that the cam shaft is rotated step by step under the control of a solenoid S which is impelled at predetermined time periods from a neon lamp timing device, comprising the lamp N and

impulse relay A. The cam assembly is moreover, a standard unit which may be used in different circumstances and controls 22 spring sets with six different positions. The full number of cams is not employed in the present instance and the chart shown in Fig. 2 shows the effect of the various cams which are used in this particular arrangement. The cam contacts which are operated in each of the six positions are designated in the figure by a black circle or a bar.

If it is assumed with regard to controller No. 2, that the cam shaft is in its first position, cam contacts C1, C9 and C22 will be operated, thereby lighting the green signal lamps GNS for the north-south road, and the red signal lamps REW for the east-west road, while at the same time over cam contacts C1, a circuit is complete from the valve rectifier 1VLV by way of a tapping on the common resistance 13 for charging the condenser QA. After the initial period of for example, 10 seconds has elapsed, the condenser QA will be charged sufficiently to cause the neon lamp N to flash over, thereby operating relay A which at armature a1 energizes the solenoid S which advances the cam shaft into its second position. In this position, as will be evident from the chart, the signal lamps already lit are maintained and over cam springs C2 and the adjusting switch shown a charging circuit is again completed for the condenser. Four such adjusting switches are shown in the drawings and it should be explained that the terminals of these switches connect with suitable tapping points on the common resistance 13. To meet the requirements of the invention the resistance now connected in circuit must be very high to ensure that the condenser charges slowly, and for this reason the adjusting switch in question is preferably turned round into its extreme position where it will be understood that it connects with the end of the common resistance 30 shown.

During progressive working this particular timing circuit will have practically no effect on the operation of the controller since with the normal operation of the master timer a light pulse is delivered over the control leads before it becomes operative. As already explained this light pulse is obtained by including a high resistance in the pulse leads at the banks of the master timer, and as a result relay B only is operated in the controller, thereupon at its armature b1 in conjunction with the cam contacts C7 completing low resistance charging circuit for the condenser QA. Almost immediately therefore the neon lamp N flashes and causes the controller to step to position 3. Non-inductive resistances are connected across the control leads as shown in order to guard against false operation owing to surges and inductive discharges.

In accordance with the change of the cam contacts, the green lights for the north-south road are now replaced with amber lights ANS, and over cam contacts C3 and the adjustable resistance switch a circuit is completed for the condenser QA to control the duration of the amber signal. With this arrangement although the phase of the amber signal may be changed when an adjustment is made in the cycle at the master timer, its actual duration remains constant since it is determined by the setting of the local adjusting switches and is not influenced by the relays connected to the control leads.

In case it should be desired to show the amber signal simultaneously to both roads, as is the requirement of certain administrations, this may be

achieved by bridging the amber circuits by means of the strap and switch 14 shown in the drawings. After the duration of the amber warning period the solenoid S again operates to step the cam shaft to position 4 and the control signals are then completely reversed while over cam springs C4 a charging circuit is completed for the condenser QA which provides an initial timing period of 10 seconds for the east-west road. When this period has elapsed, the solenoid S steps the cam shaft to position 5 and although the signals previously showing are retained, the charging circuit for the condenser QA is completed by way of the very high resistance as a result of the adjusting switch associated with cam contacts C5 being turned into an extreme position.

Here again this second comparatively long time period has practically no effect upon the controller during normal progressive operation since a heavy pulse will be received from the master timer meanwhile, which results in the operation of both relays B and C, and the latter at armature c1 in conjunction with the cam contacts C18 steps the cam shaft into its final position 6. In this manner the controllers are stepped progressively depending on the connections to the banks of the timing switch, and providing the master timer is functioning correctly, the time periods of their "stop" and "go" signals will be directly regulated therefrom.

If, however, for any reason the master timer should fail in such a manner that no further impulses are delivered over the control leads, the individual controllers will continue to function satisfactorily at somewhat longer time intervals as a result of the charging circuits completed over the cam contacts C2 and C5. Moreover, in case a particular line fault on the control conductors should maintain operated one or both of the signal relays at the controller, the latter will continue to function at somewhat shorter time intervals as determined by the initial timing circuit completed over cam contacts C1 and C4.

In addition to the normal operation of the system and the necessary safeguards against failure, it is also possible to provide special features such as for example causing all controllers to show a red signal to all approaches thereby effecting a complete hold up of the traffic. This condition may be brought about instantaneously from the master timer by the operation of the manual switch which closes the contact marked ARS in the drawings, thereby connecting potential to a common wire 15 extending to all controllers which results in the operation of a relay AR in each. Relay AR at armature ar1 disconnects the operating circuit for the controller which is thus brought to rest in the position to which it is set, at armature ar2 opens the circuit of the green and amber signal lamps and at armature ar3 bridges the circuit of the red signal lamps so that both sets are lighted. It will be appreciated from a consideration of the chart that in all positions of the controller one or other of the red signals will be showing and therefore the connection described will be effective no matter in what position the controller is brought to rest.

For the purpose of switching the controllers on and off a further common wire 16 is provided which connects with the switch contact CSS3 at the master point and a relay CS in each controller. The operation of the switch CSS disconnects the master timer insofar as its control function is concerned by opening the circuit to the valve rectifier VLV at springs CSS1 and CSS2,

and at springs CSS3 connects potential to the common lead 16 to operate a relay CS in all controllers, which thereupon at armatures cs1 disconnect the respective controllers from the alternating current mains. This method of control is preferred to the alternative, whereby the relay is operated to connect up the controller since a failure at the master timer might then result in the individual controllers becoming disconnected.

Arrangements are also provided by means of a special manual switch at each controller whereby the all red feature may be brought into action at that particular point only. When this manual key is operated, the springs ARS1 and ARS2 are actuated, thereby disconnecting the circuit for the green and amber signal lamps and also connecting together the red signal lamps so that both sets show simultaneously regardless of the position of the controller.

In case it should become necessary under certain circumstances for a particular controller to be operated manually, the required circuit changes are brought about by the operation of a further key which actuates the springs MAN1 and MAN2 to disconnect the timing circuit of the controller and also connects the solenoid S in circuit with a push button PB. The operation of the push button by the officer in charge causes the controller to step through its cycle and any desired time periods may be allowed.

As already explained, a supervisory lamp MFA is provided which is located in a conspicuous position at the master timer and arranged to flash in synchronism with the stepping switch. Failure of the switch to step due to some mechanical trouble will therefore be evident by the failure of the supervisory lamp to light and the traffic engineer is thus acquainted of the fault. An indication is also given of the blowing of the main fuse or similar trouble in which event the lamp is extinguished.

In case the master timer is switched on at a time when certain of the controllers are out of phase, the correct phase setting between each will be restored when the stepping switch in the master timer has made one complete revolution.

The application of the progressive system of control to an existing system of road-pad-operated controllers is also contemplated according to the invention. In this connection it will be realized that when a system of road-pad-operated controllers for example of the type described in British specification No. 356,102 previously referred to, is working under heavy traffic conditions, the occurrence of the maximum timing period will be the rule rather than the exception, and under these circumstances the controllers become in effect fixed time controllers working on their maximum timing limits. In the application of the invention to such systems it is proposed to associate each controller with a master timer in much the same manner as that disclosed in the accompanying drawings and arranged so that control will only be exercised therefrom when the controller attains its maximum timing limit. For this purpose it is proposed to so modify the existing controllers that when the maximum timing limit is reached the signals will not immediately change but rather the circuits will be put into a condition such as to be responsive to the regulating pulses from the master timer. This is best achieved by placing the maximum timing circuit in each controller under the control of the relay which is operated from the master timer. With this arrangement when a number

of controllers attain their maximum timing limit they will be temporarily held in this condition and thereupon released progressively under the control of the relays operated from the master timer. It will be understood however, that the master timer and associated control relays are operated continuously but their operation is only effective when the controllers in question are working on their maximum timing limits.

10 The actual circuits might be similar to those disclosed in British specification No. 355,741 which shows a traffic control arrangement of generally similar type provided with neon lamp timers. Referring now to Figure 3 illustrating an enlargement of the diagram outlined in heavy dash lines in Figure 2, the operation of this embodiment of a road pad operated controller will be described. In this illustration road pads or traffic detectors are omitted from the main street 15 designated as A and provided only in the cross street designated as B. The right of way is accorded to cross street B upon actuation of a traffic detector in this street and after a period of 20 right of way in this street which varies between a minimum and a maximum depending upon the frequency of further traffic actuation in this street the right of way is automatically transferred to the main street A. It is accorded to this street for a minimum period before it can be 25 transferred again to street B, in response to actuation in the latter street. Timing means is also provided so that in the event of absence of actuation on street B for a relatively long period the right of way may be automatically transferred to 30 the cross street to care for pedestrian traffic or any cross traffic which may have failed to actuate the road pad. The apparatus can readily be arranged to disconnect this timing means so that right of way will remain continuously on street A 35 until actuation by traffic on street B.

The construction of the apparatus illustrated in Fig. 3 is similar to that illustrated as a part of the individual controller in Figure 2 particularly in the arrangement of the cam shaft and means 40 for operating the cam shaft and in the use of a condenser and discharge tube timing arrangement. In Figure 3 it will be noticed that there are 16 cams and 56-71 represent contacts operated by these cams.

50 The scheme of representation shown under numeral 72 is as follows: In one position, for example, A, contacts 57, 60, 62, 63 and 67 are closed. If magnet 29 is now energized and de-energized the cams will be notched or shifted to position B. 55 Contacts 62 and 63 remain closed. Contacts 57, 60 and 67 are now open, but contacts 58, 61 and 69 are closed. The operation is similar as the cams are notched successively to positions C, D, E and F. In this figure the notching magnet 29 is again indicated and whenever energized, operates the 3 60 switch members 93, 94, and 95 which represent schematically the 3 circuit closers operated by the plunger of solenoid 29. Member 93 is the one 65 which is made as soon as the motion of the plunger starts and 94 and 95 are the two which are made at the end of the motion of the plunger upon energization of the solenoid. Elements 96 and 97 represent relays, and whenever either relay is energized, magnet 29 is energized because 70 current flows from wire 98 through wire 31, magnet 29, wire 30, and, in case relay 97 was energized, through armature 100, contact 101, wire 102 and wire 99 and, in case relay 96 was energized through armature 103, contact 104, wire 102

and wire 99. Wires 98 and 99 are connected to a source of power.

As will appear later, when all traffic has ceased on street B, the apparatus will eventually come to rest in position F. In this position contact 56 5 is closed lighting the A street green signal, and contact 59 is closed lighting the B street red signal. Thus, the right of way is being given to the highway and vehicles may proceed on that street. At the same time, contact 65 is closed 10 allowing current to flow from wire 98 through contact 65, resistance 105, wire 106, wire 107, wire 108, condenser 109 and wire 99, and the voltage of condenser begins to build up at a rate determined by the value of resistance 105. Assume that this 15 resistance is adjusted so that condenser 109 is charged up to the critical voltage of tube 110 in thirty seconds. However, even though condenser 109 reaches the critical voltage of tube 110, tube 110 does not become conducting because its discharge circuit is open at contact 63 and in addition is open at armature 111 and contact 112. In applying applicant's invention to this apparatus the discharge circuit also includes the contacts c2 of the master control relay C and is held 20 open until contacts c2 close. Thus, the system 25 remains inactive and right of way continues to be shown to the highway.

If a vehicle approaches on the cross street operating one of the vehicle actuated control devices located there, the circuit between wires 10 30 and 11 will be closed momentarily allowing current to flow from wire 98 through wire 113, relay 114, circuit 11 and 10, wire 115 and wire 99. This would effect only a momentary closure of relay 114 were it not for the locking circuit consisting of contact 116, armature 117, wire 118, contact 62, (contact 62 being made in position F), and wire 119, this locking circuit being made when relay 114 operates. When relay 114 operates, it 40 closes contact between armature 111 and contact 112 partially, completing the circuit shunting condenser 109 through wire 120, so that as soon as contacts c2 of the master control relay have 45 closed the circuit through the tube 110 is completed. Tube 110 becomes conducting and the energy stored in condenser 109 discharges through relay 97 operating it momentarily. This closes contact between armature 100 and contact 101, energizing magnet 29 which in turn rocks 50 the notching mechanism. As soon as the core of the solenoid has been fully attracted, circuit between wires 89 and 90 is made which shunts resistance 121 directly across the terminals of condenser 109. Resistance 121 is of a very low 55 value, its only purpose being to prevent arcing, when switching mechanism 94 closes. This allows any energy remaining in condenser 109 to be dissipated in resistance 121, tube 110 becomes non-conducting, the energizing circuit of relay 97 is consequently broken, armature 100 separates from contact 101 and magnet 29 becomes 60 de-energized. This allows the notching mechanism to return to its normal position, and in so doing, to shift or notch the cams from position F 65 to position A.

In position A, contact 57 is closed, lighting the A street yellow signal, and contact 60 is closed, lighting the B street yellow signal. At the same time contact 63 is closed insuring that the discharge circuit of condenser 109 through the tube 110 shall remain closed regardless of subsequent action to relay 114. At the same time contact 67 is closed allowing current to flow from wire 98 through contact 67, resistance 122, wire 123, 70 75

wire 124, wire 125, condenser 126 and wire 99, and in a similar manner the voltage of condenser 126 begins to build up at a rate determined by the value of resistance 122. Assume that the period required is 2 seconds. At the end of two seconds, condenser 126 reaches the critical voltage of tube 127 and the energy stored in condenser 126 discharges through tube 127 and relay 96. Relay 96 operates, closing circuit between armature 103 and contact 104, energizing magnet 29, which in turn rocks the notching mechanism. When the solenoid core has moved to its extreme energized position, switching device 95 closes circuit between wires 91 and 92, placing resistance 128 directly across the terminals of condenser 126. Resistance 128 is similar to resistance 121 and performs the same function for condenser 126 that resistance 121 performs for condenser 109. The remaining energy of condenser 126 being dissipated in resistance 128, relay 96 becomes de-energized, de-energizing magnet 29 which allows the notching mechanism to again move forward the cams, which shift from position A to position B.

In position B, contact 58 is closed lighting the A street red signal, and contact 61 is closed lighting the B street green signal. The right of way is now being given to B street and the vehicle which approached there may cross. In position B, contact 69 is closed and current flows into condenser 126 through resistance 129, and condenser 126 reaches the critical voltage of tube 127 in 3 seconds. At this moment tube 127 becomes again conducting and the notching operation proceeds in the very same manner previously described, advancing the cams from position B to position C. In moving from position B to position C, there is no change in the signal lights, contact 58 and 61 remaining closed. Contact 62, however, is open, which breaks the locking circuit of relay 114 which drops to its de-energized position. In addition, contact 71 is closed, and since relay 114 is de-energized, current flows from wire 98 through resistance 130, contact 131, armature 132, contact 71, wires 123, 124 and 125, condenser 126 and wire 99, and similarly the voltage of condenser 126 begins to build up at a rate determined by resistance 130. Assume that this resistance is set so that condenser 126 builds up to the critical voltage of tube 127 in 7 seconds. Assuming that no further cars approach on the cross street, then after 7 seconds, condenser 126 will discharge through tube 127, performing the very same steps of the notching operation described previously. This notches the cams from position C to position D.

In position D, contacts 57 and 60 are again made, lighting both the A and B street yellow lights. In addition, contact 68 is made which closes the charging circuit of condenser 126 through resistance 133. Assuming that resistance 133 is set to charge condenser 126 up to the critical voltage of tube 127 in 2 seconds, then condenser 126 will discharge after 2 seconds and the notching operation will proceed again as described previously, shifting the cams from position D to position E.

In this position, contacts 56 and 59 are made, lighting the A street green signal and B street red signal, and the right of way has returned to the highway. At the same time contact 70 is made which charges condenser 126 through resistance 134 as previously described. Assume that the period timed, as determined by the setting of resistance 134, is 5 seconds. Then after 5 seconds, the advancing operation will again pro-

ceed, as previously described, and the cams will be moved from position E to position F. We have reached the condition described at the beginning, and charging of condenser 109 starts, contact 65 being made. But after condenser 109 has reached the critical voltage of tube 110, it does not discharge through said tube because the discharge circuit is open, as described previously.

I have thus described the operation of the device assuming that only one car approached on the cross street. It will be noticed that after right of way has been showing on the highway for a certain length of time, right of way is immediately callable to the cross street, should a vehicle approach there. But if a vehicle should approach on the cross street at any time after the cross street has lost right of way, and before right of way has been given to the highway for a certain length of time, relay 114 will operate and lock in, closing the discharge circuit of condenser 109, but, no discharging of condenser 109 can take place until it has been charged to the critical voltage of tube 110, and this cannot take place until right of way has been showing on the highway for a certain length of time.

If right of way has been transferred to the cross street in response to a vehicle approaching there, and a second vehicle approaches on the cross street before the end of the 7 second period which is timed in position C, relay 114 will operate, causing armature 132 to touch contact 135, which shunts resistance 136 across the terminals of condenser 126, at the same time interrupting the charging circuit of condenser 126. It will be noticed that the length of time circuit between wires 10 and 11 remains closed depends entirely upon the length of time the wheel of the vehicle is on ramp 5. And this again depends entirely upon the speed of the vehicle. The slower the vehicle is travelling, the longer is this length of time, and the faster the vehicle is travelling, the shorter is this length of time. Consequently, adjustable resistance 136 is shunted across the terminals of condenser 126 for a period of time dependent entirely upon the speed of the vehicle operating relay 114. If the vehicle is moving slowly, this time will be longer and practically all the energy stored in condenser 126 will be dissipated in resistance 136, and thus when the energizing circuit is re-established, charging of condenser 126 will start with practically no stored energy in the condenser, and the time required to charge it up to the critical voltage of tube 127 will be practically 7 seconds. If the vehicle is travelling fast, the time of discharge, and consequently the amount of discharge will be small. Thus, when the energizing circuit is re-established, charging of condenser 126 will start with some remaining stored energy, and the period timed will be the period necessary to charge condenser 126 from the voltage existing at the moment to the critical voltage of tube 127. The time period will be shorter by the amount of time that would have been necessary to charge condenser 126 from zero voltage to the voltage to which it had been reset. Thus it appears that the amount of reset depends upon the length of time the energizing circuit is interrupted.

As soon as traffic ceases to approach on B street, condenser 126 will discharge through tube 127, notching or advancing the cams to position D, and from then on the operation is as described above.

Should vehicles approach continuously on B street, continually resetting condenser 126, right

of way would remain indefinitely on the cross street to the disadvantage of the highway unless some limitation is imposed upon the length of time the cross street may retain right of way. It will be noticed that in position C, contact 64 is closed which allows charging current to flow into condenser 109 through resistance 137. Assume that resistance 137 is so adjusted that condenser 109 will reach the critical voltage of tube 110 in 20 seconds. This condenser is not reset by approaching vehicles, and if traffic continues at the end of 20 seconds, condenser 109 will discharge through tube 110, operating relay 97 which energizes magnet 29, and the mechanism notches to position D as described previously, provided contacts c2, forming a part of the discharge circuit through the tube, are closed. It will be seen that the master timer through relay C is able to control the transfer of right of way from street B by the maximum timer. The difference is that relay 97 also operates armature 138 which touches contact 139 which allows current to flow through relay 114, operating it. The energizing circuit made at armature 138 is only momentary and relay 114 would not remain energized, (its locking circuit being broken at contact 62) were it not for contact device 93 which is made as soon as notching mechanism 26 begins to move. This completes circuit between wires 78 and 79 which provides a temporary locking circuit. Contact 62 is made in position D and as a matter of fact, is made slightly before the notching mechanism has completed its clockwise notching movement, and is so adjusted that contact 62 is made just before circuit between wires 78 and 79 is broken, maintaining relay 114 in an energized position. Thus, while some vehicles have lost right of way before they have had sufficient time to cross the intersection, the system remains in such a condition that without requiring any additional actuation of the B street vehicle actuated device, right of way will revert to B street at the end of the highway right of way period.

It will be noticed that right of way is being given to B street in position B although the resettable timer has not begun to operate. This period, in this case 3 seconds, is the period provided to allow one or more vehicles which may be waiting on B street to get into motion, and presumably the last of such waiting vehicles is actually in motion when the mechanism notches the cams to position C.

If no vehicles are waiting on B street, right of way will be given to the highway and may remain there indefinitely, thus preventing pedestrians from crossing the highway. It is sometimes desirable to provide a system which will occasionally shift right of way to the cross street even though there are no vehicles waiting thereon, stopping the highway traffic and allowing pedestrians to cross the highway. This may be accomplished through contact 66 which is made in position F. This charges condenser 126 through resistance 139', and this resistance is adjusted so that condenser 126 is charged to the critical voltage of tube 121 in 2 minutes. This notches the cams to position A and from then on they automatically advance themselves through the succeeding positions. Of course, should vehicles approach while cams are in position C, they will reset condenser 126, as described previously. But if no vehicles at all approach right of way will shortly be returned to the highway and highway traffic may proceed.

It will be obvious that this automatic transfer

of right of way to the B street in the absence of traffic actuation can be disconnected by means of a switch which may conveniently be placed in the timing circuit between cam contacts 66 and timing resistance 139.

In describing the operation of the system, I have shown the device as exhibiting the signal lights in the usual sequence, namely, green, yellow, red, yellow, green. It frequently is desirable to omit the showing of yellow when the shift is from red to green, and continue to show a red light while a yellow light is being given to the street which is losing right of way. This can be easily accomplished by providing that the cam under contact 57 operates the contact only in position A, that the cam under contact 58, operates the contact through position B, C, and D, that the cam under contact 59 operates the contact through positions E, F, and A, and that the cam under contact 60 operates the contact in position D only. Obviously by suitable arrangement of the cams any other desired signal sequence may be obtained.

For the purpose of manual operation a switch 140 is opened, thus disconnecting the timing mechanism from the lights. The lights may be operated manually by simply pressing push button 141, which, upon each functioning, energizes magnet 29 thus advancing the cams through their cycle and in so doing transfers right of way from one vehicle lane to the other.

Referring further to Figure 3 and the condensed illustration shown in Figure 2 the maximum timing circuit in this case is that associated with the condenser 109 and the discharge circuit therefor has to be closed over contacts 63 or armature 111. In the arrangement contemplated according to the invention this discharge circuit would only be completed by the relay responsive to the controlling pulses from the master timer.

As illustrated this control may be provided for by omitting the direct connection between relay 97 and armature 111 which would be employed where this controller is used as an isolated system independent of any master control and by running this circuit through the contacts c2 of the master control relay C. It will be noted as described above that the discharge tube 110 and the relay 97 are a part of the timing circuit serving as a maximum timer in position C of the cams through the cam contact 64 and also serving as a minimum timer on street A in position F of the cams through the cam contact 65. Thus it will be seen that the operation of the maximum timer in position C on the cross street will be controlled by the master control relay C and it will also be seen that the completion of the time period to permit transfer of right of way to the cross street in response to cross street actuation will in position F also be under the control of master control relay C, thus permitting the master timer to control the transfer of right of way to the cross street in response to actuation and also to control the retransfer of right of way to the main street in the event of traffic on the cross street being sufficiently heavy to produce extension of the cross street right of way period up to the maximum.

Referring now to Figure 4 the present invention is shown applied to govern operation of a traffic signal controller of the full-actuated type, having detectors in both main and cross streets. Such a full-actuated controller is disclosed in British Patent 356,102, and application of the invention to this type controller provides for controlling the instant of release of right of way

from each street if the right of way is prolonged up to a maximum.

In Figure 4 there is represented timer 139 of British Patent 356,102 and when current is applied at its terminals E, E it times the maximum duration of right of way for traffic on one of two intersecting streets, for example, A street, causing release of right of way from A street by the separation of armature 57 from contact 56 at the end of the maximum time period. Timer 137 is the corresponding maximum timer for the other or B street controlling release of right of way from B street by its armature 86 and contact 87. Each of these timers serves as a time delay relay, the time delay period being determined by a condenser-gas discharge tube timing unit. When current is applied to terminals E, E of timer 139, relay 17 is energized closing armature 21 against contact 20 to complete a charging circuit for condenser 24 over high resistance 19. When condenser 24 has acquired a voltage above the conducting potential of gas discharge tube 26, and assuming the contact c2 closed, a circuit paralleling condenser 24 is completed through tube 26 and relay 27 is energized by the charge stored in the condenser. Relay 27 locks in via its contacts 30 and its armature 57 breaks at contact 56 a control circuit for causing transfer of right of way. When current is disconnected from terminals E, E relay 17 is deenergized, at contact 20 the condenser charging circuit is interrupted, and at contact 32 a circuit is completed via low resistance 33 to completely discharge the condenser in preparation for timing the next interval.

In accordance with the present invention as shown in Figure 4, the circuit through tube 24 and relay 27 paralleling the condenser is not completed unless or until relay C is energized by the master timer to close its contacts c2. Thus, after the condenser charging period of the maximum timer 139 is completed, the instant at which right of way may be released from A street by operation of relay 27 to separate contacts 56-57 is determined by the time of operation of relay C by the master timer. Similarly, termination of the B street right of way by maximum timer 137 is governed by the time of operation of relay B. In this way at one or more full-actuated controllers the transfer of right of way at the end of the maximum period may be controlled by a master timer in accordance with the invention.

The term "controller" is used herein broadly to designate the mechanism located at the individual intersection for operating the signals through their cycle of right of way indications and in the present embodiment this controller includes a timing device for determining the time periods of display of the different right of way and cautionary change indications in the cycle, but which timing device is normally superseded in effect by an external timer in determining the period of the right of way indications in certain parts of the cycle. This external timer is designated herein as "master timer" or "master timing means" for convenience in distinguishing from the individual or local controller and as representative of its functions of maintaining the cycle of the individual local controllers in predetermined time relation. The master timer it will be observed includes a timing device providing closely spaced periodic impulses, and a cyclic switching device having distributing units for providing impulses at different preselected points in the cycle to the individual controllers, all the units being operated

in unison step by step by the impulses of the timing device. In this respect the master timer acts as a common timing means for the several individual local controllers. In the embodiment shown in Fig. 3 the controller is operated by its timing device subject to modification of the timing by traffic actuated means.

It will be understood that various changes in construction and rearrangement of the parts of my system might be made without departing from the spirit of my invention as defined in the claims.

I claim:—

1. A signalling system for interfering lanes at a crossing including signals to accord and interrupt right of way over said lanes, means, when operative, operating to cyclically accord right of way to the respective lanes for periods of time for the control of traffic, said means including a device for predetermined the time of the beginning and ending of the said periods, a control station, means including timing mechanism at said station for sending spaced impulses spaced cyclically, the said second cyclic operation being of less duration than the first cyclic operation, and means responsive to said impulses to affect said device to shorten said periods by advancing the time of ending of said periods.

2. A signalling system for an intersection of traffic lanes, including signals to accord and interrupt right of way in said lanes, controller means operating to cyclically accord right of way alternately to the respective lanes, said means including a timing device for determining the time periods of said accord of right of way, a control station, means including timing mechanism at said station for sending cyclically spaced impulses, the said second cyclic operation being of less duration than the first cyclic operation, and means in said controller responsive to said impulses to affect said device to shorten said periods at a certain point in the cycle of the first cyclic operation to normally control said first cyclic operation.

3. In a traffic control system for a plurality of intersections of traffic lanes having at each intersection a signal and controller operating the same through a cycle for according right of way successively to such lanes at such intersection, a central master timer normally operating through a shorter time cycle than the cycle of said controller for controlling the phase relation between such controllers and maintaining them in step with the master time cycle, said master timer comprising a periodic impulse generator, a step-by-step rotary switch having a plurality of contact positions and connected to be stepped periodically and cyclically through such positions in the master time cycle by said impulse generator, said switch having a plurality of contact banks and cooperating energized wipers, and a common driving magnet operated by said generator, for operating said wipers in unison from step to step on said contact banks, each said controller including timing means operating during a part of its cycle to time accord of right of way and cause transfer of right of way from one lane to the next at the end of its timing period, each bank having a plurality of spaced contacts arranged to be successively energized by one of said wipers, and means connecting one of said contacts in each of said banks to a separate one of said controllers to accelerate the respective timing means of the several controllers at predetermined positions of said switch normally to

control the relation of such transfers of right of way by such controllers to the master time cycle.

4. A signalling system including, in combination, a plurality of signalling means to be installed one adjacent each of a plurality of intersections of traffic lanes and adapted to accord and interrupt right of way in said lanes, a plurality of controllers for said intersections and connected each to one of said signalling means to operate the same through a time cycle to transfer right of way alternately between the intersecting lanes, impulse responsive means individual to each controller and adapted on accord of right of way to one lane to be operated to cause transfer of right of way to another of the intersecting lanes by said signal and thereby control the time cycle of the signal, a master timing means connected to all of said controllers and comprising a cyclic step by step rotary switching device for supplying impulses to said impulse responsive means in the several controllers at different predetermined points in its cycle for determining the time phase relation of such transfer of right of way by said controllers, said switching device including a plurality of impulse units one for each controller to have a different phase relation with said switching device, driving means for stepping said switching device and impulse units in unison through such cycle, a condenser, power leads and a resistance connected to said condenser to vary its charge over an interval of time, an electronic tube connected to said condenser and operable responsive to a predetermined state of charge on said condenser to activate said driving means, means acting upon operation of said tube to reset said condenser charge, and means for adjusting said resistance to vary said time interval and proportionately vary the time cycle of all said controllers.

40 5. A signalling system, including in combination, signalling means to be installed adjacent an intersection of traffic lanes and adapted to accord and interrupt right of way in said lanes, a cyclically operating controller for said intersection and connected to said signalling means to control the same, master timing means connected to said controller to control the operation thereof, said controller including a condenser, power leads and a resistance connectible to said condenser to vary the charge on the same over an interval of time, a switching device connected to said signals to operate the same, driving means for said switching device, an electronic tube connected to said condenser and operable responsive to a predetermined state of charge on the same to activate said driving means, and control means when operable connecting said resistance between said condenser and power leads, and means forming a part of said master timing means to operate periodically said control means.

60 6. A signalling system, including in combination, signalling means to be installed at an intersection of traffic lanes and adapted to accord and interrupt right of way in said lanes, a cyclically operating controller for said intersection and connected to said signalling means to control the same, master timing means connected to said controller to control the operation thereof, said controller including a condenser, power leads and a resistance connectible to said condenser to vary the charge on the same over an interval of time, a switching device connected to said signals to operate the same, driving means for said switching device, an electronic tube connected to said condenser and operable responsive to a

predetermined state of charge on the same to activate said driving means, and control means adapted when operated in a part of said controller cycle for connecting said resistance between said condenser and power leads, and means forming a part of said master timing means and connected to said controller to operate periodically said control means, and further means in said controller including a higher resistance and normally connected to said condenser to similarly vary the charge on the same but at a considerably slower rate than said first named charge varying means such that if said first named charge varying means fails to operate the slower rate charging means will vary the charge on said condenser to the point where said driving means is activated.

7. A signalling system including in combination, signalling means at an intersection of traffic lanes and adapted to accord and interrupt right of way in such lanes, a cyclically operating electrically driven controller for operating the signalling means to transfer right of way between the lanes periodically at a certain time rate, master timing means, a single circuit connecting said master timer to said controller, said master timer operating cyclically to transmit to said controller electrical impulses of different values at different times over said circuit, means forming a part of said controller and responsive to only one of said impulses to cause said controller to operate more rapidly through portions of its cycle, and further means forming a part of said controller and responsive to the other impulse to cause said controller to operate more rapidly through another portion of its cycle.

8. A traffic control system for a plurality of intersections of traffic lanes, including in combination right of way signalling means at each intersection, traffic actuated means in one of the lanes at each intersection, a plurality of controllers one at each intersection and connected to said signalling means and adapted to operate the same through a cycle in which right of way is accorded alternately to the lanes for time periods, means forming a part of each said controller and connected to be operated by actuations of the traffic actuated means associated therewith to prolong the accord of right of way in the lane of said traffic actuated means beyond said time period, means in each said controller to provide when operating a maximum time limit to such prolonged accord of right of way in such lane, and a master timer connected to all of said controllers for periodically rendering said maximum limit means operative in the several controllers in pre-determined time relation, whereby if traffic actuation at the respective intersections is sufficient to prolong right of way up to the maximum limit the periods of accord of right of way in the lanes of the traffic actuated means will be maintained in pre-determined time phase relation at the several intersections.

9. A traffic control system for a plurality of intersections of traffic lanes having at each intersection signalling means, traffic actuated means in the lanes, a controller connected to said actuated means and to said signalling means for operating said signalling means to transfer and accord right of way to the lanes alternately for time periods in response to actuation of said traffic actuated means, said time periods being extendable in response to further actuation in a lane having right of way, maximum timing means comprising a condenser, means for charging said

condenser at a slow rate and means when connected to said condenser responsive to a predetermined charge on said condenser to limit extension of said time periods, and a master timer 5 operating for cyclically connecting said responsive means to said condenser in each controller in a predetermined time relation with the others whereby transfers of right of way occurring by 10 operation of said maximum timing means at all 10 intersections take place in predetermined time relationship.

10. A traffic control system for the intersection of interfering traffic lanes including signalling means adapted to accord and interrupt right of way in the lanes, traffic actuated means in the 15 lanes, a controller connected to said signalling means and said traffic actuated means and having alternate signal control positions through which it is adapted to operate to cause said signalling means to accord right of way alternately 20 in the respective lanes in response to actuation

of the traffic actuated means, said controller including a timing device energized in one such alternate position for timing such accord of right of way and prolonging such accord of right of way responsive to actuation of the traffic actuated means during such accord of right of way to the lane of the latter traffic actuated means, circuit means for operating the controller from such one position to the other to cause the signalling means to interrupt such accord of right of way 10 when the circuit of said circuit means is completed, a second timing device operating at the end of a maximum time period in such one position to prepare said circuit for completion and maintaining said circuit so prepared thereafter 15 while said second timing device remains operated in such one position, and said system including a cyclic master timer for periodically completing said circuit when prepared.

20 PERCY BAILEY RENSHAW.
